UNITED STATES PATENT OFFICE.

PHILIP A. DESLAURIERS, OF ST. PAUL, MINNESOTA.

DESIGN FOR A SIDING-PLATE.

SPECIFICATION forming part of Design No. 22,091, dated December 27, 1892.

Application filed May 5, 1892. Serial No. 431,971. Term of patent 14 years.

To all whom it may concern:

Be it known that I, PHILIP A. DESLAURIERS, a citizen of the United States, residing at St. Paul, Ramsey county, Minnesota, have invented and produced a new and original Design for a Siding-Plate for Sheet-Metal Building-Fronts, of which the following is a specification, reference being had to the accompanying drawings, illustrating the same.

10 In the drawings Figure 1 is a plan view and Fig. 2 a cross section on the line 2—2 of Fig. 1, illustrating my design which consists of a rectangular portion containing a series of diagonally running parallel lines 1 intercepted by vertically extending lines 3 each two sets of the diagonal lines being connected by the

two opposite vertical lines so as to inclose a space 2, the whole being surrounded by a border 4 formed by the lines 5 and 6.

The leading features of my design consist 20 of the rectangular portion containing the lines as above described and surrounded by the border formed as specified.

What I claim is:—

The design for a siding plate for a building front shown and described.

In testimony whereof I have hereunto set my hand this 22d day of April, 1892.

PHILIP A. DESLAURIERS.

In presence of—

T. D. MERWIN,

H. S. JOHNSON.
